[57] CLAIM

The ornamental design for a golf ball cleaner and carrying bag, as shown and described.

DESCRIPTION

FIG. 1 is a perspective view, looking toward the right side, of a preferred embodiment of my golf ball cleaner and carrying bag illustrating my new design;

FIG. 2 is a front elevational view of FIG. 1, the other side being a mirror image thereof;

FIG. 3 is a bottom plan view of FIG. 1;

FIG. 4 is a right side elevational view of FIG. 1;

FIG. 5 is a top plan view of FIG. 1; and,

FIG. 6 is a left side elevational view of FIG. 1.

The broken line showing a golf ball in FIG. 5 is included for illustrative purposes only, and forms no part of the claimed design.
